UNITED STATES PATENT OFFICE.

FREDERICK W. QUIDAS, OF BROOKLYN, NEW YORK.

CLIP FOR DEVELOPING-TRAYS.

1,125,092.

Specification of Letters Patent.

Patented Jan. 19, 1915.

Application filed May 23, 1913. Serial No. 769,516.

To all whom it may concern:

Be it known that I, FREDERICK W. QUIDAS, a citizen of the United States, residing at Brooklyn, in the county of Kings and State of New York, have invented new and useful Improvements in Clips for Developing-Trays, of which the following is a specification.

My invention relates to developing trays in which a clip is used for a holding device for plates or films while being developed.

The object of my invention is to produce a simple device in the form of a clip which can be manufactured cheaply and at the same time be easy to attach and detach from the developing tray.

A further object is that it can be adapted to trays for holding small photographic dry plates, and such narrow and long plates as are used for stereoscopic purposes.

A further object is that it enables one to use a plurality of such clips or arms for two or more plates at a time, the number of such clips or arms being in proportion to the number of plates being developed.

A still further object is to produce a plate holding device which does not need to be attached to the inside of the tray on which said clip can be used.

Referring to the drawings: Figure 1, shows a cross-section view of the tray with the clip in position. Fig. 2, a cross-section view of tray having a modification of the clip shown in Fig. 1. Fig. 3, a top plan view of the tray, utilizing said clip. Fig. 4, a side view of the clip. Fig. 5, a perspective view of Fig. 4. Fig. 6, a modification of clip. Fig. 7, a perspective view of Fig. 6.

By referring to the drawings, in which like reference characters designate corresponding parts, the tray 15 can be made of any transparent substance, preferably glass, so that progress of the development of the plates placed therein can be watched without removing them from the tray until fully developed.

At the one end of the tray is formed a partial top 9 which acts as a reservoir, so that when the tray is stood upright for the inspection of plate or film during development, the solution will not run out.

As shown in Fig. 3 of the drawings, two or more clips can be used for developing two or more plates 11, as well as one clip for developing one plate.

At the upper end of the tray, Figs. 1 and

2, a detent 12 is formed. At 13 an offset with finger depression 14, Fig. 3, is formed for facilitating the gripping of the plate for removal.

As shown in Fig. 4, 3 is a curved end adapted to engage in the recess 1, Fig. 1, while the upper curved portion 6 of the clip engages over the open end 10 of the partial top 9 of the tray.

Between 3 and 6 the clip is "bowed" or curved as shown at 4, so that when the clip is pressed against the partial top 9, the "bowed" portion 4 is flattened out, thus allowing the curved portions 3 and 6 to engage the respective points 1 and 6, Fig. 1, which will make the clip secure by the contracting spring action of the "bowed" portion 4. 4^a shows the bowed portion flattened against the partial top, shown in dotted lines, and representing the corresponding portion of the partial top as shown in Fig. 1. At 8 is a hooked point which serves the purpose of holding the plate at that particular place, while the plate is being made secure in the tray by the action of the spring arm forcing and holding the plate up in the detent 12. The reference numbers correspond to those in Fig. 1.

Figs. 6 and 7 show a modified form of clip 85 which performs a different function in securing itself to the tray, although it is the same in principle. The recess 2, Fig. 2, is made longer to accommodate the modified form of clip. The formation of this recess 90 2, Fig. 2, is the same as the recess 1, Fig. 1, except for length to accommodate the longer spring extension 5 of the clip. In other respects the construction is identical with the form shown in Figs. 4 and 5, the points 6, 95 (Fig. 6) and points 7 (Fig. 7) are used for the same purpose; also, the hooked point 8 performs the same function. To fasten this modified form of clip to the tray, it is only necessary to place the point 5, Figs. 6 and 7, 100 in the recess 2, Fig. 2, and force the other extremity or arm of clip over the point 10 of the partial top 9, Fig. 2, so that the curved portion 6 engages said point 10, when the action of the spring 5 will tend to produce 105 a clamping action between the recess 2 and point 10.

In developing plates, the clip being in position, the plate is placed at the hooked point 8, at the extremity of the arm of the 110 clip, the plate 11 being pressed downward causes said arm to bend sufficiently to allow

the upper end of the plate to engage in the 5
detent 12 placed or formed at the upper end
of the tray, the spring action of the arm of
the clip causing the plate to be held rigidly
in said detent 12.

To remove the plate 11, the reverse action
takes place; *i. e.*, by placing the finger in the
depression 14, then pressing the plate downward,
the arm of the clip yields correspondingly
until the upper end of plate is free or
disengages from under the detent 12, after
which the plate is easily removed.

I do not wish to be understood as limiting
myself to the details of construction and ar-
rangement as herein described, as variations
and modifications can be made in the fea-

tures of construction and arrangements in
the adaptation of the device to various con-
ditions of use without departing from the
spirit and scope of my invention.

20

I claim:

A developing tray having a partial over-
hanging top, and a spring clamp formed to
span and engage said top and having a de-
pending spring arm adapted to engage one 25
end of a photographic plate and hold the
same with its opposite end in engagement
with the opposite end of said tray.
